[57] CLAIM

The ornamental design for a razor storage holder, as shown and described.

DESCRIPTION

FIG. 1 is a top perspective view of a razor storage
holder showing my new design;

FIG. 2 is a front elevational view thereof, the rear surface being plain;

FIG. 3 is a side elevational view thereof, the side opposite being a mirror image;

FIG. 4 is a top plan view thereof;

FIG. 5 is a bottom plan view thereof; and,

FIG. 6 is a bottom perspective view thereof.

FIG. 1FIG. 2*FIG. 3*FIG. 4*FIG. 5
